UNITED STATES PATENT OFFICE.

MELVIN A. CAUDLE, OF VANWOOD, WEST VIRGINIA.

DUMPING CAR.

Application filed January 19, 1924. Serial No. 687,341.

To all whom it may concern:

Be it known that I, MELVIN A. CAUDLE, a citizen of the United States, residing at Vanwood, in the county of Raleigh and 5 State of West Virginia, have invented certain new and useful Improvements in Dumping Cars, of which the following is a specification, reference being had to the accompanying drawings.

10 This invention relates to certain improvements in dumping cars and has relation more particularly to a device of this character especially designed and adapted for use in connection with mining and it is an 15 object of the invention to provide a novel and improved car of this character of sufficient strength to permit the same to be directly loaded by a shot or blast together with means whereby the load of the car may 20 be readily and conveniently discharged therefrom.

Another object of the invention is to provide a novel and improved device of this general character especially designed and 25 adapted for use in connection with carrying out of slate from a mine and wherein the car is constructed in a manner whereby the load thereon may be readily and conveniently discharged at either side of the 30 car.

It is also an object of the invention to provide in connection with a car of this kind novel and improved means to prevent shooting of the slate during a loading operation, surface kinking or spreading the rails 35 of the trackway upon which the car travels.

The invention consists in the details of construction and in the combination and arrangement of the several parts of my improved dumping car whereby certain important advantages are attained and the device rendered simpler, less expensive and otherwise more convenient and advantageous for use, as will be hereinafter more 45 fully set forth.

The novel features of my invention will hereinafter be definitely claimed.

In order that my invention may be the better understood, I will now proceed to describe the same with reference to the accompanying drawings, wherein:—

Figure 1 is a view in side elevation illustrating a car constructed in accordance with an embodiment of my invention;

55 Figure 2 is a vertical sectional view taken

longitudinally of the car as herein disclosed and substantially at the transverse center thereof;

Figure 3 is a view in end elevation of my improved car as herein disclosed, a second 60 position of certain of the parts being indicated by dotted lines, such position being taken when the body is in dumped position;

Figure 4 is a transverse sectional view 65 taken centrally of the car as illustrated in Figure 1;

Figure 5 is a detail view partly in elevation and partly in section illustrating the means herein employed for use in connection with the car to prevent surface kinking or spreading of the rails; 70

Figure 6 is a view in section taken through Figure 5, showing a section through the rail and ramp.

As disclosed in the accompanying drawings, A denotes the front and rear trucks of a car, said trucks travelling upon a trackway B. The trucks A are connected by the longitudinally disposed sills 1 arranged at opposite sides of the trucks A and which have their forward end portions connected by the transversely disposed and underhung end sills 2, said sills 2 extending a predetermined distance beyond opposite sides of the trucks A. Operatively engaged with the central portions of the end sills 2 and with the trucks A is a draft bar 3. 75

Mounted upon each of the trucks A is an upstanding bolster or plate 4 herein disclosed as in the form of an inverted V. The apex portions of the bolsters or plates 4 constitute bearings for the pivot or fulcrum member 5 comprised in the tilting body or bottom of the car. The portions 6 of the member 5 directly engaged with the bolsters or plates 4 are cylindrical in cross section and associated with each of said portions 6 is a holding strap 7, the extremities of which being suitably secured, as at 8, to the side edges or walls of the bolsters or plates 4. 90

By this means the member 5 is effectively maintained in applied position yet permitted to have rocking movement in either direction whereby the dumping body or bottom of the car may be tilted toward either 95 side of the car structure.

The car body or bottom comprises the transversely disposed slats 9 having their central portions suitably connected to the member 5 and their outer end portions se- 100

cured to the longitudinally disposed beams 10. The upper portions of the bolsters or plates 4 at opposite sides are connected by the brace beams or members 11 whereby the 5 strength of the car in its entirety is materially increased.

Associated with each side of the car is a laterally swinging frame F, said frame as herein disclosed comprising a plurality of 10 longitudinally spaced posts 12 having their lower or inner end portions pivotally connected, as at 14, with similar end portions of the end sills 2 and an intermediate or central sill 15. The upper or outer end portions of the posts 12 have secured thereto a beam 16 and the posts 12 are of such length that when the same are in substantially a vertical position the beam 16 will have close contact with the inner face of a 15 beam 10 whereby the dumping body or bottom of the car is supported in substantially a horizontal position and against tilting or dumping movement at such side of the car structure. The frame F is normally maintained raised through the medium of the 20 spring 17, said spring having one end portion, as herein disclosed, secured to a sill 1 and its opposite end portion operatively engaged with a post 12.

30 Each of the frames F is normally locked against inward swinging movement by the latches 18 pivotally engaged with the end portions of the sills 1 and engageable with a pin or keeper 19 carried by the end post 12.

35 The upper portions of the bolsters or plates 4 have interposed therebetween and supported thereby a longitudinally disposed beam 20 positioned above and in parallelism with the draft bar 3. Supported by the bar 40 and the beam 20 is a vertically disposed shank or pin 21 upon which are rotatably mounted the connected pulleys 22 and 23. The upper pulley 22 being of less radius than the lower pulley 23. The lower pulley 45 23 constitutes the power pulley and has operatively engaged therewith a flexible cable 24 which is of a length to extend beyond an end of the car and terminates in a loop or eye 25 with which the motor or traction 50 means is adapted to be coupled in order to impose a requisite pull to cause the desired rotation of the pulleys 23 and 22.

55 The upper pulley 22 has operatively engaged therewith the flexible member 26 the outer end of which being adapted to be selectively engaged with an inwardly disposed hook member 27 carried by each of the frames F in accordance with the direction toward which it is desired that the 60 dumping car body or bottom tilts.

65 The opposite end portions of the pivot or fulcrum member 5 is provided with the outstanding and horizontally disposed arms 28, said arms being of such a length and position as to intersect and be under the

70 path of travel of a frame F as the same is swung inwardly and downwardly whereby the dumping body or bottom is caused to tilt at the side of the car to which the inwardly swinging frame F is operatively engaged. By changing the connection of the flexible cable 26 with either of the hook members 27, the dumping body or bottom may be caused to tilt at the side of the car required.

75 In practice, the car is run to a position where the blast or shot of slate is to be made so that the loosened slate will be received directly upon the dumping body or bottom of the car, the strength of the car structure being such to withstand the resultant strain imposed thereon. By this means the car is loaded without requiring the loosened material to be manually handled. After the car has received a shot 80 the same is transported to the place of dumping.

85 In order to prevent surface kinking or spreading of the rails of the trackway at 90 the time of a shot I find it of advantage to provide adjacent each of the rails and between the same a supplemental track or ramp 29 having its upper surface extending above the upper surface of the rails and its 95 end portions suitably rounded so that the trucks may ride upwardly upon such supplemental track or ramp. With the car mounted directly upon the supplemental track or ramp at the time of a shot, it will be understood that no injury will be imposed upon the rails of the trackway. In 100 order to permit the desired use of the rails or ramp 29 each of the wheels of a truck has its tread of pronounced width, as illustrated in Figure 6 of the accompanying drawings, with the rail flange 30 positioned in substantially the longitudinal center of 105 such tread surface.

110 From the foregoing description it is thought to be obvious that a dumping car constructed in accordance with my invention is particularly well adapted for use by reason of the convenience and facility with 115 which it may be assembled and operated, and it will also be obvious that my invention is susceptible of some change and modification without departing from the principles and spirit thereof and for this reason I do not wish to be understood as 120 limiting myself to the precise arrangement and formation of the several parts herein shown in carrying out my invention in practice except as hereinafter claimed.

125 I claim:—

1. In combination with a car body, a 125 tilting body mounted thereon, a swinging frame mounted upon the body and serving to hold the tilting body against movement, means for swinging the frame in one direction, and means carried by the tilting body 130

engageable with said frame when moved in one direction to impart tilting movement to the tilting body.

2. In combination with a car body, a tilting body mounted thereon, a swinging frame mounted upon the body and serving to hold the tilting body against movement, means for swinging the frame in one direction, means carried by the tilting body engageable with said frame when moved in one direction to impart tilting movement to the tilting body, and means for normally maintaining the frame in a position to hold the tilting body against movement.

15 3. In combination with a car structure, a dumping body mounted thereon for swinging movement in opposite directions, separate means for holding the body against tilting movement in opposite directions, means selectively engageable with said holding means for adjusting the same into inoperative position to permit the body to tilt in one direction.

20 4. In combination with a car structure, a dumping body mounted thereon for swing-

ing movement in opposite directions, separate means for holding the body against tilting movement in opposite directions, means selectively engageable with said holding means for adjusting the same into inoperative position to permit the body to tilt in one direction, and means carried by the dumping body engageable by either of the holding means when moved into inoperative position to impart tilting movement to the body. 30

35 5. In combination with a car structure, a shaft rotatably supported thereby, a dumping body movable with the shaft, frames supported by the structure and arranged at either side of the shaft for holding the body against tilting movement, means for moving either of the frames into inoperative position to permit tilting movement of the dumping body, and outstanding arms carried by the shaft with which a frame engages when moved into inoperative position to impart tilting movement to the body. 40 45

In testimony whereof I hereunto affix my signature.

MELVIN A. CAUDLE.
